DESIGN FOR A COMBINED GLOVE AND MITTEN

Anne Rhea, New York, N. Y., assignor to Julius Kayser & Co., New York, N. Y., a corporation of
New York

Application June 12, 1941, Serial No. 101,421

Term of patent 3½ years

To all whom it may concern:

Be it known that I, Anne Rhea, a citizen of the United States of America, residing at New York, New York, in the county of New York, have invented a new, original, and ornamental Design for a Combined Glove and Mitten, of which the following is a specification, reference being had to the accompanying drawing, forming part thereof.

Fig. 1 is a front view of the glove with its end part extended;

Fig. 2 is a back view of the same;

Fig. 3 is a back view of the glove with the end part shown folded over the back of the glove;

Fig. 4 is a front view of the glove with the fingers folded back into the pocket showing the glove worn as a mitten; and,

Fig. 5 is a back view of Fig. 4.

I claim:

The ornamental design for a combined glove and mitten, as shown.

ANNE RHEA.
